UNITED STATES PATENT OFFICE.

JOSEPH BRESLOVE, OF PITTSBURGH, PENNSYLVANIA, ASSIGNOR TO THE CLECO CORPORATION, OF NEW YORK, N. Y., A CORPORATION OF NEW YORK.

FLOATING TOY.

Application filed June 29, 1923. Serial No. 648,438.

To all whom it may concern:

Be it known that I, JOSEPH BRESLOVE, a citizen of the United States, residing in the city of Pittsburgh, county of Allegheny, and 5 State of Pennsylvania, have invented a certain new and useful Improvement in Floating Toys, of which the following is a specification.

This invention relates to a toy for children 10 which is constructed to resemble a house boat or the like and which will be provided with means for supporting it on the water. It may, if desired be used to house other small floating toys and it provides a novel and interesting form of toy constructed in a strong 15 and practically unbreakable manner.

The object of this invention is to provide such a toy which is constructed so that it may be disassembled or assembled readily and 20 shipped in a "knocked down" condition whereby convenience in shipping is provided.

A further object of the invention is to provide an article of the character above 25 mentioned having its parts simply constructed and arranged so that said parts may be readily assembled by a small child without difficulty to produce a novel toy and to provide an interesting and instructive occupation for the child.

With these objects and other objects which may hereinafter appear, in view, I have devised the particular arrangements of parts set forth below and more particularly 30 pointed out in the claims appended hereto.

Reference is to be had to the accompanying drawing, forming a part hereof, in which—

Figure 1 is a front elevation of my im- 40 proved floating toy;

Figure 2 is a side elevation of the same;

Figure 3 is a sectional view on the line 3—3 of Figure 1, looking in the direction of the arrows; and

Figure 4 is a sectional view on the line 4—4 of Figure 2 looking in the direction of the arrows.

Throughout the various views of the drawings, similar reference characters designate similar parts.

In the preferred embodiment of my invention as illustrated in the accompanying drawings, 1 indicates one of the floats or pontoons for supporting the boat house, and 55 forming part of the same. 2 indicates a

similar pontoon or float. These floats may be of any suitable material capable of floating in the water and may be of any desired shape according to the construction of house boat they are required to support. 60

A preferred design for said floats is as shown in the accompanying drawing wherein the same consist of air filled metal chambers. The floats in their operative position are spaced apart and are connected by a 65 suitable brace which is made extensible or telescopic to enable the floats to be readily separated when the boat house is disassembled.

The float 1 is provided with a tubular extension 3 which forms a part of the brace 70 above mentioned and said extension 3 is intended to slide into a complementary extension 4 on the float 2. Each of the floats 1 and 2 is provided with an upwardly projecting flange 5 to enable said floats to be 75 detachably secured to the side walls 6 and 7 of the boat house. Said side walls 6 and 7 consist of a pair of plates having their lower edges provided with a flange 8 which rests upon the floats 1 and 2. The side walls 80 6 and 7 are provided at their lower edge with suitable perforations which register with like perforations in the flanges 5 so that small bolts 9 may pass through the walls 6 and 7 and through the flanges 5 to se- 85 curely attach said walls to the floats 1 and 2. At 10 is shown the back of the boat house which has its lower corners cut away as at 11 to enable said back plate to fit the curve of the floats 1 and 2. Said back plate is pro- 90

vided at its opposite side edges with inwardly bent flanges 12 which are perforated to receive bolts 13 extending through the sides 6 and 7. Said bolts 13 secure the back firmly in position and connect the same to 95 the side walls 6 and 7 as above pointed out. The front plate or wall 14 is connected to the side walls in a similar manner by being provided with inwardly bent flanges 15 at its opposite side edges which flanges re- 100 ceive bolts 16 extending through the side walls 6 and 7 to connect the front plate 14 to said side walls.

To further reinforce the structure thus provided, a brace rod 17 is used which connects the front plate 14 with the back plate 10 and screws 18 extend through the front and back plates and into the rod. 105

From the foregoing it will be seen that a rigid box-like structure is provided, to 110

which the floats are securely attached. The roof is shown at 19 and the same consists of a flat plate having its longitudinal side edges inwardly bent to form flanges 20 which co-operate with flanges 21 on the upper edges of the sides 6 and 7 to enable the roof 19 to be slid on and off, so that small floating toys or the like can be readily placed within the house boat through the roof opening.

The front edge of the roof plate 19 is downwardly bent as at 22 to provide a flange which abuts against the front member 14 to limit the movement of the roof plate 19 and properly position same over the roof opening. The side walls 6 and 7 and the back plate 10 may be ornamented in any suitable manner and may be provided with window openings such as at 23 and 24. The front is shown provided with window openings 25 and with openings 26 through which small floating toys or the like may be moved out of the boat house. The openings 26 may be closed by a sliding plate 27 which forms a door to cover both of said openings and said plate may be secured in its lowered position over the openings 26 by means of a bolt or screw 28. It will be seen from the construction above described that the space between the two floats 1 and 2 is substantially open and small floating toys may be placed within the house and rest upon the water, and by opening or raising the door 27 said toys may be caused to move out of the boat house through said openings 26.

The manner in which the various parts of the device are assembled and secured together by small bolts enables the device to be readily assembled by a child, providing an interesting and instructive occupation.

From the foregoing it is obvious that my invention is not to be restricted to the exact embodiment shown but is broad enough to cover all structures coming within the scope of the annexed claims.

Having described my invention, what I claim is:

1. A toy comprising a pair of separated and independent floats, a telescopic brace connecting the same, a plurality of separable plates, means for detachably joining the edges of said plates together to form the same into an enclosure, a flange on each of said floats and means for detachably connecting parts of the enclosure to said flanges.

2. A toy comprising side walls, a front and a back, a roof and a pair of floats, flanges on said floats, means for securing the side walls to said flanges, means for detachably securing the front and back to the side walls, a removable brace connecting said front and back and means on the side walls for slidably receiving the roof.

3. A toy comprising side walls, a front and a back, a roof, a pair of floats, projecting extensions on said floats adapted to telescope to produce a brace for connecting the floats, upwardly projecting flanges on the floats, means for securing the side walls to said flanges, inwardly extending flanges on the front and back, means for securing said front and back to the side walls, a brace extending between the front and back at their lower ends, and flanges on the upper edges of the side walls for slidably receiving the roof.

Signed at the city of Pittsburgh, county of Allegheny and State of Pennsylvania, this 26 day of June, 1923.

JOSEPH BRESLOVE.
